United States Patent Office

Des. 195,647
Patented July 9, 1963

195,647

ANCHOR HOLDER

Wilfred A. Hanggi, 728 Van Buren, St. Paul, Minn.
Filed Dec. 6, 1962, Ser. No. 72,753

Term of patent 14 years

(Cl. D54—11)

FIG. 1

FIG. 2

FIG. 3

FIG. 4

FIG. 5

I claim:

The ornamental design for an anchor holder, as shown.
